UNITED STATES PATENT OFFICE.

DAVID H. HEINDEL, OF HUNTINGTON, INDIANA.

ELEVATOR.

1,318,556.

Specification of Letters Patent.

Patented Oct. 14, 1919.

Application filed August 9, 1918. Serial No. 249,095.

To all whom it may concern:

Be it known that I, DAVID H. HEINDEL, a citizen of United States, residing at Huntington, in the county of Huntington, State 5 of Indiana, have invented certain new and useful Improvements in Elevators; and I do hereby declare the following to be a full, clear, and exact description of the invention, such as will enable others skilled in the 10 art to which it appertains to make and use the same.

The invention relates to an elevator and more particularly to the class of manually operated lifts for use in buildings or the 15 like.

The primary object of the invention is the provision of an elevator or lift of this character, wherein the occupant of the carrier thereof can manually operate the same 20 for the automatic raising and lowering of the carrier, the mechanism for the raising and lowering of the carrier being of novel form so that there is no possibility of the sudden dropping of the carrier when in 25 raised position.

Another object of the invention is the provision of an elevator or lift of this character, which eliminates the necessity for the use of motor power to effect the raising and 30 lowering of the carrier, and the mechanism for raising and lowering said carrier is readily and easily manually operated without excessive labor on the part of the attendant or occupant when it is desired to 35 ascend or descend in the elevator or lift.

A further object of the invention is the provision of an elevator or lift of this character which is extremely simple in construction, thoroughly reliable and efficient in its 40 operation and inexpensive to manufacture and install.

With these and other objects in view, the invention consists in the features of construction, combination and arrangement of 45 parts as will be hereinafter fully described, illustrated in the accompanying drawing and pointed out in the claim hereunto appended.

In the accompanying drawing:

50 Figure 1, is a fragmentary elevation of an elevator or lift constructed in accordance with the invention.

Fig. 2, is a sectional view on the line 2—2 of Fig. 1, looking in the direction of the 55 arrow.

Fig. 3, is a fragmentary vertical longitudinal sectional view.

Fig. 4, is a sectional view on the line 4—4 of Fig. 1.

Fig. 5, is a sectional view on the line 5—5 60 of Fig. 1.

Fig. 6, is a sectional view on the line 6—6 of Fig. 1.

Similar reference characters indicate corresponding parts throughout the several 65 views in the drawing.

Referring to the drawing in detail, A. designates generally the elevator or lift guide frame which comprises spaced vertical guides 10 formed in their outer sides 70 with weight channels 11 for movement of the balancing weights 12 carried at the free ends of weight cables 13 which are trained over and travel upon guide pulleys 14 journaled in the upper ends of the vertical 75 guides 10, the opposite ends of the cables 13 being suitably fixed to the top of the carrier or lift B proper, vertically slidable in the guide frame A and constructed in a manner presently described.

The carrier or lift B proper, comprises a platform 15, having upstanding therefrom the side posts 16 which support a cross piece or head 17, to which are fastened the cables 13, the posts 16 being vertically channeled for receiving the tracks 18 of the vertical guides 10 of the guide frame A in 80 which travels the carrier or lift B, proper.

Mounted on one post 16 of the carrier or lift B proper, is a substantially U-shaped 90 bracket 19 having arranged therein a power pulley 20, journaled upon a stud axle 21, mounted in the bracket 19 and the adjacent post 16 of the lift or carrier B, the pulley 20 being formed with a belt wheel 22 over 95 which is trained an endless belt 23, the same being also trained over a belt driving wheel 24, which is fixed to a crank shaft 25 journaled in the bracket 19 and adjacent post 16 of the carrier or lift B proper, the shaft 25 100 being formed with a crank handle 26 for manual operation.

Trained about the driving pulley 20 is a cable 27 which has one end fixed to the base of the frame A and its opposite end fixed to 105 a hook-like fastener 28 mounted in the head of said guide frame A, the stretch of the cable 27 being in vertical alinement with the pulley 20 so that on rotation of the lever the coil of the cable 27 will be fed about the pulley 110.

ley 20 when rotated, thereby causing the pulley to travel upon the cable 27 and thus raise or lower the carrier or lift B proper, in the guide frame A, as will be apparent.

5 The belt drive wheel 24 is formed with a brake wheel 29 about which is trained a brake band 30, the opposite ends of which are loosely connected through the medium of the links 31 with a brake operating arm 10 32 on opposite sides of its swinging axis, the arm 32 being supported to swing upon a pivot 33 fixed in a hanger 34 mounted on the carrier or lift B proper. Connected to the 15 arm 32 remote from the point of connection of the brake band 30 therewith, is a coiled retractile spring 35 which is also connected to the head of the carrier or lift B, and the function or office of this spring 35 is to normally hold the brake band 30 in frictional, 20 binding or braking position upon the brake wheel 29, and thereby retarding the movement or holding the lift or carrier B proper against movement. On exerting pressure upon the arm 32 against the resistance of the 25 spring 35, the brake is released so that the carrier or lift B proper, can be raised or lowered by manually operating the hand crank 30 by an occupant or attendant upon the carrier or lift B proper. When pressure is re-

leased from the arm 32 the brake will be 30 automatically applied for holding the lift or carrier B proper, against movement, thereby sustaining the same in its adjusted ascending or descending position.

From the foregoing it is thought that the 35 manner of use and construction of the invention will be clearly understood and therefore a more extended explanation has been omitted.

What is claimed is:

40 In an elevator, the combination with a guide frame, a cable attached to its head and base, a lift movable in the frame, and a pulley wheel carried by the lift and around which the cable makes a coil; of a crank 45 shaft mounted in the lift, wheels on this shaft and on the shaft of said pulley, a belt connecting the wheels, a brake drum fast on the crank shaft, a band brake around the drum, a pivoted lever controlling the action 50 of said band, and a spring normally moving the lever to apply such band to the drum.

45 In testimony whereof I affix my signature in the presence of two witnesses.

DAVID H. HEINDEL.
